UNITED STATES PATENT OFFICE.

FRANK H. DOUGHERTY, OF PHILADELPHIA, PENNSYLVANIA.

RADIATOR VALVE.

Application filed July 30, 1924. Serial No. 729,000.

My invention relates to valves for venting radiators of cold air and vapors and preventing the escape of the heating medium therefrom and more particularly of the type 5 of valve forming the subject of U. S. Letters Patent No. 1,403,162, granted January 10, 1922, to Andrew Heldrich, assignor to Leskole Air Valve Company, Inc. This patented valve is so constructed as to permit the 10 escape of relatively cold air and vapors from the radiator as the steam is admitted to the radiator and to prevent the escape of the steam or other heating medium from the radiator after the latter has become filled 15 therewith, but is inoperative to prevent the inflow of air to the radiator following the opening of the valve as upon the occurrence of a slight vacuum in the radiator or when the steam pressure for any reason becomes 20 insufficient to maintain the valve closed.

While in certain heating installations the admission of air to the radiators and other parts of the system through the vent valves upon the occurrence of such conditions is un- 25 objectionable, in others it is desirable to prevent such admission and thereby maintain in the radiators and other parts of the system the slight vacuum which is induced following the shutting off of the steam or upon the 30 cooling down of the system so that upon the readmission of steam thereto the necessity of clearing the system from residual air will be avoided, and it is therefore an object of my invention to provide in a valve 35 of the general character of that patented in said patent means for automatically preventing the admission of air to the radiator or other part of the heating system with which the valve is connected upon the formation 40 of a vacuum in the system or upon sufficient reduction of pressure therein to cause an opening of the valve. The present invention may therefore be in some respects considered as an improvement on the said 45 patented valve with a view to rendering the same satisfactorily operative for use in connection with heating systems from which it is desirable to prevent the admission of air upon the opening of the vent valves.

Various other objects, advantages and novel features of construction and arrangement comprehended by my invention will hereinafter more fully appear.

In the accompanying drawing I have 55 illustrated a valve constructed in accordance with one manner of performing my inven-

tion, Fig. 1 being a vertical central section thereof with certain parts shown in elevation, the valve being in "open" position, and Fig. 3 is a similar view of the valve in 60 "closed" position. Fig. 2 is an enlarged fragmentary view in central section of certain of the parts as shown in Fig. 1, like numerals being used to indicate the same elements in the several figures. 65

As shown, the valve comprises a connection 1 provided with screw threads 2 for connecting the valve to a radiator, the connection having an internal passage 3 leading into a well 4 in the upper end of which is disposed a cup 5 conveniently stamped from sheet metal and having a centrally disposed conveniently conical valve seat 6 cooperative with a suitable main valve poppet 7 disposed at the lower end of the vertically extending valve stem 8. Partially within the cup may be disposed a deflector 9 which comprises a cylindrical wall 10 provided with circumferential ports 11 positioned above the upper end of the cup, above which and at the upper extremity of the wall is a transversely disposed plate or web 12 centrally perforated for the passage of the valve stem, the deflector thus, in effect, forming an inverted cup disposed above the cup 5 and closed save for the ports 11 in its wall and the perforation through which the valve stem projects. Above and extending upwardly from the cup 5 is arranged a cylindrical valve body or shell 13 closed at its 80 upper extremity by a head having a depending flange 14 engaging over the extremity of the shell. This head may also comprise a flat portion 15 bounded by the flange and in turn bounding a central vertically extending neck 16, conveniently threaded externally for the reception of a removable cap 17 of suitable form. For convenience of assembly the lower end of the body may be turned inwardly and then carried down so as to seat in the cup between its wall and the wall of the deflector and the several parts soldered or otherwise secured together at this point, and the cup similarly secured in the upper end of the well so as to firmly 85 maintain the several parts in the relation described and prevent any leakage between the adjacent surfaces thereof. The head may also be fixedly secured on the extremity of the shell by frictional engagement or by 90 soldering or in any other suitable way. 95

Fixedly secured on the valve stem which 100

110

extends therethrough and above the deflector is a preferably metallic, hollow control member 20 comprising an inverted bell-shaped portion 21 having at its lower extremity an outwardly extending flange 22 and rim 23 lying adjacent the wall of the shell, the bell-shaped portion of the member being provided with a transversely extending disk 24 at its mouth disposed substantially in the plane of the flange 22.

The several parts to which reference has hitherto been made bear close similarity to these disclosed in said Patent No. 1,403,162 and function to permit the escape of air past the valve poppet 7 when steam is admitted to the radiator and to close said poppet on its seat 6 when all the air has been expelled therefrom and a certain amount of steam has entered the valve, following which the poppet is maintained in closed position as shown in Fig. 2 to prevent the escape of steam through the valve so long as sufficient steam pressure is maintained behind the poppet, all as more fully disclosed in said patent and to which reference may be made for a description of the manner in which these functions are performed.

The means now to be described are provided for the purpose of preventing an inward flow of air through the valve and thence to the radiator and other parts of the system upon the opening of the valve following the decrease of pressure or occurrence of vacuum in the system and which, in the absence of such or equivalent means, would thereupon occur. With this end in view I dispose upon the upper end of the valve stem an auxiliary valve poppet 30 conveniently of inverted conical form which is cooperative with a suitably formed seat 31 in a valve disk 32 which is preferably of circular form and flat on its upper and lower faces. This disk is disposed above an inwardly directed flange 16' formed at the upper end of the neck 16 and which at its center may be dished or cupped downwardly as at 16" and provided, for the passage of the valve stem, with a central perforation 34 preferably of somewhat greater diameter than the stem so as to allow the latter a little play therein. The wall of the dished portion 16" of the flange is provided with one or more ports 35 through which the air or vapors expelled through the valve can pass from the interior of the shell 13 to the space or chamber 36 beneath the disk 32, and for preventing the disk from adhering or sticking to the upper face of the flange 16' and for affording a suitable seat for the disk I provide a small circular ridge or rim 37 on the upper surface of the flange and of somewhat smaller diameter than the disk, the upper extremity of the ridge being preferably quite sharp so as to present a relatively small area of contact with the under face of the disk. For venting any air or

vapor through the movable cap 17 the latter is provided with a suitably positioned port 38.

The operation of the valve constructed substantially as hereinbefore described and attached to a radiator or other suitable point in a heating system through the medium of the connection 1 is as follows: Starting with the system in cold condition and with the valve in open position as in Fig. 1, upon the admission to the radiator of the steam or other heating medium the relatively cold air or vapors contained in the radiator are forced into the valve past the poppet 7 and thence through the ports 11 into the interior of the shell 13. From this point the air and vapors continue upwardly through the ports 35 and thence between the disk 32 and ridge 37 and out of the valve through port 38, the disk lifting slightly from the ridge under the pressure of the air and vapors to permit their passage and immediately closing back on the ridge upon the decrease of such pressure. After substantially all of the air and vapors have been expelled and the steam begins to enter the valve, condensation of the steam takes place within the former with consequent accumulation of water of condensation within the cup 5 and lower part of the shell 13, following which, as more fully explained in said patent No. 1,403,162, the control member 20 is rapidly moved or "kicked" upwardly thus closing the main valve poppet 7 on its seat and preventing further passage of steam into the cup. The parts of the valve are thus brought to the positions shown in Fig. 2 in which they substantially remain until the pressure of the steam in the radiator and behind the poppet 7 falls below a predetermined point when the control member is no longer sustained in raised position with consequent lowering of the poppet to open the valve. Of course while the valve is closed the auxiliary poppet 30 is raised from its seat in the disk 32 as shown in Fig. 2, the disk meanwhile remaining on its own seat so that free communication is permitted between the exterior of the valve and the interior of the shell 13. Simultaneously with the opening of the poppet valve 7, however, the auxiliary valve is once more seated in the disk and the latter tightly closed against the ridge 37 by the weight of the valve stem and attached parts assisted by the differential pressure, if any, between the external atmosphere and the interior of the system, thus preventing any reserve flow of air into the interior of the valve and in turn to the interior of the system and also maintaining any slight vacuum which may be induced in the latter following the shutting off of the steam or for any other cause. Thus, upon readmission of steam to the system the necessity of expelling therefrom residual air contained therein is obviated.

It will be noted that as the valve stem 8 is not closely confined in the perforation 34 both the auxiliary poppet 31 and disk 32 are free to adjust themselves on their respective seats so as to make at all times a close and adequate contact therewith, and further, that by reason of the relatively great area of that portion of the under face of the disk which is exposed to the pressure of the outgoing air only a very minute substantially vertical displacement of the disk is required to vent the air into the cap 17, or to the external atmosphere if the cap be not employed, so that any pounding of the disk on its seat and consequent wear on these parts is avoided. Moreover, by reason of the construction employed, the disk may be made of any size and weight desirable without imposing any additional burden on the control member and attached parts which might interfere with the proper functioning of the latter in closing and opening the poppet valve 7, for as the valve stem is freely movable through the disk it is free to rise and fall with respect thereto in conformity with the movements of the control member without causing any movement of the disk, the auxiliary poppet valve, however, always forming a tight closure between itself and the disk whenever the control member is lowered and the main valve poppet 7 thus brought to open position. This feature is of material importance in view of the fact that the control member and parts movable therewith should be made of relatively light weight for satisfactory operation when the valve is intended for installation in ordinary house heating systems and the like designed to operate under a minimum steam pressure or sometimes even under a slight internal vacuum.

While I have herein illustrated and described with some particularity a preferred embodiment of my improved valve I do not thereby desire or intend to limit myself specifically thereto as the various elements entering into the valve are capable of modification in minor particulars from the precise embodiments to which I have referred without departing from the spirit and scope of the invention as defined in the appended claims.

Having thus described my invention, I claim and desire to protect by Letters Patent of the United States:

1. In a radiator vent valve, the combination of a body, a main valve for controlling the admission of steam from the radiator to the body, said valve being disposed in a normally closed position when the heating system to which the vent valve is connected is in operation and in a normally open position when said system is idle, a valve stem projecting upwardly in the body from the main valve, closure means extending over the

upper end of the body and having a port, and a valve poppet carried by the upper end of the valve stem operative to prevent the ingress of air to the body through the port when the main valve is open and to permit such ingress when the main valve is closed. 70

2. In a radiator vent valve, the combination of a valve body, means for connecting the valve body to a radiator, a valve stem extending in the body, a valve at the lower end of the stem disposed in a normally open position when the heating system with which the vent valve is connected is idle and in a normally closed position when said system is in operation, and a valve poppet cooperating with a seat adjacent the upper end of the body and operative to prevent the ingress of air to the body through the port when the main valve is open and to permit such ingress when the main valve is closed. 75

3. In a radiator vent valve, the combination of a valve body, means for connecting the body to a radiator, a main valve adjacent the lower end of the body operative to prevent the admission of steam to the body when in one position and to admit steam to the body when in another position, means for closing the upper end of the body and provided with a port, a valve stem extending from the main valve through the body and through said closing means, a valve disk disposed on said closing means above the port, and a valve poppet on the upper end of the valve stem cooperative with a seat in said valve disk when said main valve is in one of said positions. 95

4. In a radiator vent valve, the combination of a valve body, means for connecting said body with a radiator, a main valve adjacent the lower end of the body operative when in raised position to prevent the admission of steam thereto and when in lowered position to admit steam thereto, means for closing the upper end of the body and provided with a port and a narrow circular ridge disposed above and surrounding the port, a valve disk having a valve seat loosely seated on the ridge and through which said valve stem freely extends, and an auxiliary poppet valve carried by the upper end of the stem and adapted when the main valve is in lowered position to close on the seat in the disk and when said main valve is in raised position to be moved away from said seat. 110

5. In a radiator vent valve, the combination of a valve body, means for closing the upper end of the body and provided with a port and a narrow circular ridge surrounding said port, a valve disk loosely seated on the ridge above the port and provided with a centrally disposed valve seat, a valve stem extending freely through the disk and said closing means, an auxiliary poppet valve 125

disposed on one end of the stem and cooperative with the seat in the disk, and a main poppet valve disposed on the other end of the stem and operative to control the admission of steam to the valve.

6. In a radiator vent valve, the combination of a valve body, means for connecting said body to a radiator, a closure for the upper end of the body provided with a port, 10 a valve stem, a main valve poppet adjacent one end of the stem for controlling the admission of steam to the body and disposed in a normally open position when the heating system to which the vent valve is attached is idle and in a normally closed position when said system is in operation, and 15 a valve adjacent the other end of the stem for preventing admission of air to the body through the port when the main valve is 20 open.

7. In a radiator vent valve, the combination of a valve body, means for connecting said body to a radiator, a closure for the upper end of the body provided with a port, 25 a valve stem, a main valve poppet adjacent one end of the stem for controlling the admission of steam to the body, an auxiliary poppet valve at the other end of the stem and movable therewith, and a valve disk 30 surrounding the stem but free therefrom and having a seat for the reception of the auxiliary poppet valve.

8. A radiator vent valve comprising a body, a valve seat adjacent the lower end of 35 the body, a main valve cooperative with said seat, means for controlling the position of said valve including a control member and

a valve stem, means extending over the upper end of the body, a valve disk cooperating with said means to control a passage therethrough, said valve stem extending freely through said disk, and a valve poppet carried by said stem and cooperating with the valve seat in the disk. 40

9. A radiator vent valve comprising a 45 body, means for connecting the valve to a radiator, a valve controlling the admission of steam to said body from the radiator, a valve stem extending upwardly from said valve within said body and projecting thereabove, means for closing the upper end of the body and comprising a port, a valve disk disposed on said means above the port, and an auxiliary valve carried by the stem and cooperative with the valve seat in said disk. 50 55

10. A radiator vent valve comprising a body, means beneath the body for connecting the valve to a radiator, a main valve for controlling the admission of steam to said body from the radiator, a valve stem extending upwardly from said valve through said body, means for closing the upper end of the body and provided with a port and a ridge surrounding and disposed above the port, a valve disk loosely seated on the ridge, 60 and an auxiliary valve carried by said valve stem and operative to seat in a valve seat formed in said disk when said main valve is open and to be lifted clear of said seat when said main valve is closed. 65

In testimony whereof, I have hereunto set my hand this 10th day of July, 1924.

FRANK H. DOUGHERTY.

Certificate of Correction.

It is hereby certified that in Letters Patent No. 1,586,787, granted June 1, 1926, upon the application of Frank H. Dougherty, of Philadelphia, Pennsylvania, for an improvement in "Radiator Valves," errors appear in the printed specification requiring correction as follows: Page 1, line 60, for the numeral "3" read 2, and line 61, for the numeral "2" read 3; page 2, line 122, for the word "reserve" read *reverse*; and that the said Letters Patent should be read with these corrections therein that the same may conform to the record of the case in the Patent Office.

Signed and sealed this 13th day of July, A. D. 1926.

[SEAL.]

M. J. MOORE,
Acting Commissioner of Patents.
